ARTHUR R. EARNSHAW, OF WYNNEWOOD, PENNSYLVANIA

REFRIGERATION

Application filed March 25, 1931. Serial No. 525,145.

This invention relates to refrigeration and more particularly to mechanical systems in which condensation and evaporation of a volatile media takes place during the refrigerating cycle, and separation of the heavier and lighter gases involved has been effected by washing, or absorption of the refrigerant gas by some medium, from which it later was driven out.

- 10 Fundamentally, the principle involved in my invention is that two gases of differing molecular weights may be efficiently separated by the use of filter screens to utilize their difference in diffusion activity, according to 15 Graham's law, in conjunction with centrifugal action to reenforce the separation by diffusion and also to carry away the diffused light gas, while at the same time the undiffused heavy gas is removed from the area of 20 diffusion. By multistage repetition of this as provided for, practically any degree of separation may be arrived at, with the expenditure of relatively little power and without the intervention of additional agents. 25 Using the system of partial pressures in an hermetically sealed circuit, the gases, once separated after leaving the evaporator, are returned to it, the refrigerant as a liquid after cooling and condensation, the light gas being 30 unchanged.

The primary object of my invention is to provide a novel-condenser-separator-evaporator refrigerating system wherein the customary refrigerant and inert gases under 35 pressure, after evaporation of the refrigerant gas into the inert gas in the evaporator, are separated by multiple-diffusion reinforced or aided by centrifugal action.

- 40 Another object of this invention is to take advantage of the difference in diffusion activity of the refrigerant and inert gases, as well as their difference in molecular weight, incident to progressive multiple-diffusion 45 through a porous medium under centrifugal action, to effect proper balancing of the flow of the respective separated gases.

A further object of my invention is to provide an apparatus adapted to the above stated 50 objects which is of simple construction, de-

pendable in operation, and not liable to get out of order under continuous use.

With these general objects in view, and others that will hereinafter appear, this invention essentially involves evaporating the 55 refrigerating fluid under pressure in an atmosphere of a relatively inert non-condensable gas, separating the two gases under pressure from the resultant mixture by filtering-centrifugal action, and condensing the re- 60 frigerating gas for re-evaporation in the recovered inert gas, with a novel means adapted thereto.

The various features of novelty whereby the invention is characterized will, herein- 65 after, be pointed out with particularity in the claims; but for a full understanding thereof, reference is to be had to the following detailed explanation of the accompanying drawing, which is a vertical section through a 70 refrigerating apparatus adapted to the present improvements.

Referring to the illustration, which shows one practical embodiment of my invention by way of example only, the numeral 10 com- 75 prehensively designates an evaporator, while 11 and 12, respectively, and similarly, indicate a gas separator and a condensing coil.

The separator 11 is enclosed within a hermetically sealed housing 13 which, in the 80 present instance, is sunk part way into a recess 14 in the top 15 of a refrigerator casing (not shown) with the hermetically connected coil 12 superimposed upon it; and the evaporator 10 disposed beneath it within said re- 85 frigerator casing. The evaporator 10 may be of the usual horizontal U-shaped cross-sectional configuration to afford an interval or space within it for the accommodation of ice pans or trays 16. The separator 11, it 90 will be noted, has the form of a horizontal rotor that tapers from the center towards its periphery, and it is secured to the tubular vertical shaft 17 of an electric motor 18, whereby it is driven at high speed; said 95 motor being enclosed by an upward axial offset 19, of the housing 13, within the confines of the condenser coil 12. The rotor 11 operates as a centrifugal filter to separate the heavier refrigerant gas from the lighter 100

inert gas mixed therewith in the process of evaporation. The rotor 11 is of composite construction, with a hollow spool-like hub 20 circumferentially flanged at the opposite 5 ends 21, and a concentric hollow ring 22, said hub and ring being joined by complementarily dished disk members 23 made from perforated sheet metal, as well as by a rigidly connected central diaphragm 24, likewise of 10 perforated sheet metal. Symmetrically arranged between the outer disks 23 and the central diaphragm 24, are diaphragms 25 which will permit ready diffusion of the lighter inert gas while resisting free passage 15 of the heavier refrigerant gas. These intermediate diaphragms 25 may be of any appropriate material permitting freer passage of the lighter gas than the heavier gas; for example, thin spruce wood with the resin extracted. There are also liner disks 26 of 20 similar material adjoining the outer perforated metal disks 23; while the tapering intervals between the several diaphragms 25 and liner disks 26 are packed with relatively 25 fine granular material, conventionally indicated at 27. The mixed gases enter the central hollow 28 of the hub member 20 of the rotor 11 from the lower portion of the tubular shaft 17 through ports 29, and from said 30 hollow pass into the packed central part of said rotor by way of apertures 30, in the circumferential wall of the hub member, immediately to opposite sides of the perforated diaphragm 24; the lighter inert gas finally 35 escaping through the perforations in the outer disk members 23 of the separator 11; while the centrifugally influenced heavier refrigerant gas enters the filler packed peripheral ring 22 of the rotor 11 by way of 40 perforations 31. The escaping lighter inert gas is collected within a sealed chamber 32 surrounding the rotor 11, while the upper and lower portions of the said chamber are afforded communication by way of longitudinal 45 tubes 33 through the hub member 20. The heavier refrigerant gas is conducted from the filler packed ring 22 of the rotor 11 by curved tubes 34 and collected in a sealed compartment 35 above the chamber 32; said 50 compartment 35 being isolated from the evaporator 10 by a plug 36 secured in the tubular shaft 17.

The mixed gases are lifted from the evaporator 10 by suction action of the rotor 11, 55 through a tube 37 which connects into the axial hollow 38 of a lower bearing member 39 for the shaft 17. This bearing member 39 is conveniently sustained in a reduced downward axial extension 40 of the separator 60 housing 13 by a surrounding flange 41. An upward neck portion 42 of the evaporator 10 surrounds the top of the tube 37 and telescopes with the downward extension 40, and is conveniently welded thereto at 43, to insure 65 a sealed juncture. With accumulation of

pressure within the chamber 32 of the rotor 11, the lighter inert gas is forced from the said chamber through a short by-pass tube 44, in the lower portion of the rotor shaft 17, into a cavity 45 surrounding said shaft 70 within the lower bearing 39. From the cavity 45 the lighter gas is conducted down into the evaporator 10 through a pipe 46, the latter having interposed in it a valve 47 which is regulatable to control the gas flow. 75

The heavier refrigerant gas is forced from the chamber 35 of the rotor 11, likewise by pressure of accumulation, into the upper portion of the tubular shaft 17 by way of ports 48, and thence into the hollow of the top shaft bearing, indicated at 49, via which it enters the condenser coil 12. Incorporated with the juncture fitting at 50 is a regulatable valve 51 whereby the flow of the refrigerant gas may be controlled. The discharge or lower portion 12' of the condenser coil 12 enters the top of the separator casing 13 and connects with another cavity 52 in the lower shaft bearing 39, from whence the condensed refrigerant is conducted, by way of a pipe 53 which has its lower end discharging laterally into the evaporator 10. Within the neck 42 of the evaporator 10, the pipe 53 is formed with a downward retroversion 54 which is designed to serve as a liquid trap, 80 wherefrom any uncondensed refrigerant gas, carried along with the liquid may, ordinarily escape through a small top aperture 55, and thence enter the pipe 17, by way of a small hole 17', for circulation through the separator 11, as aforesaid. There are also additional pin restricted apertures 56, provided at different levels down the trap 54 through which the uncondensed gas may by-pass more rapidly, as later on explained. 85

In operation and assuming the method of refrigeration by partial pressures, or the evaporation of a liquid into a gas under pressure, is understood, it will be readily seen that the mixed gas is drawn from the evaporator 10 through tube 37 and hollow shaft 17 to the separator 11; and distributes to each side of the central diaphragm 24. The space between the filter disks 25, 26 being filled with a fairly hard granular substance allows free passage of the inert gas, but it will carry said gas at the speed of the centrifuge or separator 11, without formation of disturbing currents. Incidentally the perforated metal side wall 23 strengthens the filter 26 and prevents its distortion. The mixed gas entering between the filter plates 25, 26 tends to be driven towards the circumference by centrifugal force of rotation but is retarded by a resistance, later explained. As 110 a result of this resistance a pressure is built up between the filters 25, 26 which forces the gas to pass through them by diffusion according to the degree of internal pressure. The light inert gas diffuses many times more read- 115

ily than the heavy refrigerant gas, which being acted on more strongly by the centrifugal force, is continually driven towards the circumference. This process repeated by 5 the successively disposed filters 25, 26 results in the heavy refrigerant gas working relatively slowly into the collection ring 22 through the perforations 31; while the light inert gas diffuses sideways into the conduit 10 chamber 32. From the chamber 32 the purified light inert gas returns by way of 44 and 46 to the evaporator 10, while the heavy refrigerant gas travels by way of 22, 34, 35, 17 and condenser coil 12, to said evaporator. 15 The necessary resistance to the flow of the gases through the separator 11 and the balancing of their rates of flow may be effected by regulation of the valves 51 and 47; or by the proper proportioning of the parts 32, 20 34, 35 in regard to shape and size, with reference to the amount of rotational speed they will impart to the contained gas. In the latter connection it is evident that the balance of centrifugal force tending to accelerate the flow of both gases from, or through, 25 the separator 11 is dependent upon the ratio of the rotational speed of the gases, at the point of final escape, to the speed of the gases in their respective conduits.

30 To take care of the varying amounts of refrigerant in the mixed gas during the progressive stages of the cycle of operations, the trap 54 is used. It is likely that a complete separation of the gases will not be desired, so that some uncondensed gas can 35 by-pass the trap 54 through the restricted opening 55. If during the later part of the cycle the quantity of light inert gas admixture increases at this point, it will be 40 unable to pass through 55 as readily; whereupon an increase in pressure will take place, which by lowering the liquid level will open the successive ports 56. This increased pressure will back-up around to ring 22 and slow 45 down the passage of the heavy refrigerant gas, thereby decreasing the amount of light inert gas admixture.

Attention is here directed to the provision 50 of the apertures 55, 56 with suitable means whereby their area can be varied so that only a predetermined discharge of uncondensed 55 gas may take place at a given pressure. In this manner a degree of automatic control over the purity of the refrigerant gas is ensured, since the greater the back pressure the longer said gas remains under action of the separator 11 and, consequently, the purer it will be.

Both the light and heavy gas return pipes 60 46, 12" can be so constructed that said gases may give up some or all of the heat picked up by them, after entering the separator 11, to the mixed gas leaving the evaporator 10.

In case it may be desirable to circulate oil 65 or other liquid, a wick filled tube, or it may

be a capillary tube, as indicated at 57, is provided to draw such other liquid, indicated at 57' from the bottom of the evaporator 10, to the open end 58 of the exhaust tube 37 in case said liquid is heavier than the refrigerant. If the liquid 57' is lighter, it will float on the refrigerant indicated at 10' and be carried as a spray in the mixed gases; while any excess of such liquid will return with the returning gases.

From the foregoing it is thought that my invention will be understood, but it is to be remarked that the particular combination involved is an improvement over centrifugal or diffusion separation alone; as the effect of centrifugal action is increased by filtering out the light inert gas leaving most of the heavy refrigerant gas behind. Furthermore, the known objections of the diffusion methods are overcome, since the diffused gas is removed automatically and not permitted to accumulate; the heavy refrigerant gas is not allowed to remain and increase its ratio in the undiffused gas; while the centrifugal action of the separator 11 tends to prevent the diffusion of heavy refrigerant gas by holding it to a definite course or path.

Finally, a refrigerating apparatus in accordance with my improvements is simple to construct, having little about it liable to get out of order in operation. No heat is added whether from the friction of a compressor or for the distillation of an absorption medium; the efficiency is but little lowered incident to a rise in surrounding temperature, 95 since the internal pressure that causes condensation of the refrigerant gas remains constant; while my invention ensures a more economical apparatus due to reduction of friction and less power consumption.

It is to be understood that I do not limit myself to the precise details of construction and arrangement herein shown and described, since it is obviously possible to design and proportion the centrifugal diffusion filter and the gas flow passages so that any desired differential pressures may be predetermined for the two gases to compensate for different relative allocation of the evaporator and the condenser.

Having thus described my invention, I claim:

1. The method of refrigeration which consists in evaporating refrigerant fluid in an inert gas under pressure, separating the two gases in the mixture by progressive-diffusion, and condensing the refrigerant gas for re-evaporation in the recovered inert gas.

2. The method of refrigeration which consists in evaporating refrigerant fluid in an atmosphere of relatively-inert non-condensable gas under pressure, separating the two gases composing the mixture by multiple stage diffusive-filtration, and condensing the

refrigerant gas for re-evaporation in the recovered inert gas.

3. The method of refrigeration which consists in evaporating refrigerant fluid in an atmosphere of relatively inert non-condensable gas under pressure, bringing about separation of the two gases in the resultant mixture by taking advantage of their differences in molecular weight under centrifugal-diffusion, and condensing the refrigerant gas for re-evaporation in the recovered inert gas.

4. The method of refrigeration which consists in evaporating refrigerant fluid in an atmosphere of relatively-inert non-condensable gas under pressure, bringing about separation of the two gases in the resultant mixture by taking advantage of their differences in molecular weight and diffusive-activity aided by centrifugal force, and condensing the refrigerant gas for re-evaporation in the recovered inert gas.

5. The method of refrigeration which consists in evaporating refrigerant fluid in an atmosphere of relatively-inert non-condensable gas under pressure, effecting separation of the two gases in the resultant mixture by centrifugal progressive diffusion, and condensing the refrigerant gas for re-evaporation in the recovered inert gas.

6. The method of refrigeration which consists in evaporating refrigerant fluid in an atmosphere of relatively-inert non-condensable gas under pressure, effecting separation of the two gases in the resultant mixture by combined filtering-centrifugal action, effecting maintenance of a proper balance of flow between the separated gases, and condensing the refrigerant gas for re-evaporation in the recovered inert gas.

7. The method of refrigeration which consists in evaporating refrigerant fluid in an atmosphere of relatively-inert non-condensable gas under pressure, effecting separation of the two gases in the resultant mixture by combined filtering-centrifugal action to take advantage of their difference in diffusion activity, and condensing the refrigerant gas for re-evaporation in the recovered inert gas.

8. The method of refrigeration which consists in evaporating refrigerant fluid in an atmosphere of relatively-inert non-condensable gas under pressure, separating the two gases in the resultant mixture by combined filtering-centrifugal action to take advantage of their difference in diffusion activity and molecular weight in effecting a proper balance of flow between the separated gases, and condensing the refrigerant gas for re-evaporation in the recovered inert gas.

9. The method of refrigeration which consists in evaporating refrigerant fluid in an atmosphere of relatively-inert non-condensable gas under pressure, utilizing the difference in diffusion activity and molecular weight of the respective gases incident to sep-

aration in effecting a balance of flow between the separated gases, and condensing the separated refrigerant gas for re-evaporation in the recovered inert gas.

10. The method of refrigeration which consists in evaporating refrigerant fluid in an atmosphere of relatively-inert non-condensable gas under pressure, utilizing the difference in diffusion activity and molecular weight of the respective gases under combined filtering-centrifugal action to effect separation thereof, and condensing the separated refrigerant gas for re-evaporation in the recovered inert gas.

11. The method of refrigeration which consists in evaporating a refrigerant fluid into an inert gas both under pressure, separating said fluid and gas by multi-stage combined filtering-centrifugal action, and condensing the separated refrigerant fluid at substantially the above pressure for subsequent re-evaporation in the recovered inert gas.

12. The method of refrigeration which consists in evaporating a refrigerant fluid into an inert gas under pressure, separating the resultant mixture by combined filtering-centrifugal action, automatically balancing the flow of the separated gases, condensing the separated refrigerant gas at substantially the above pressure for subsequent re-evaporation in the recovered inert gas, and further extracting heat from the condensed returning fluid and gas by absorption into the relatively colder mixture.

13. In refrigerating apparatus employing a refrigerant gas condensable at ordinary temperatures and an inert gas under pressure, evaporator means wherein the condensed refrigerant is gasified in an atmosphere of the inert gas and mixed with the latter, a progressive-diffusion-filter receiving the mixed gases and operative to separate the refrigerant gas from the inert gas, means for liquefying the refrigerant gas, and means for separately returning the liquefied refrigerant and filtered inert gas to the evaporator means.

14. In refrigerating apparatus employing a refrigerant gas condensable at ordinary temperatures and an inert gas under pressure, evaporator means wherein the condensed refrigerant is gasified in an atmosphere of the inert gas and mixed with the latter, a multi-stage diffusion-filter receiving the mixed gases and operative to separate the refrigerant gas from the inert gas, means for liquefying the refrigerant gas, and means for separately conducting the liquefied refrigerant and filtered inert gas from the separator to the evaporator without further substantial admixture.

15. In refrigerating apparatus employing a refrigerant gas condensable at ordinary temperatures and an inert gas under pressure, evaporator means wherein the condensed re-

frigerant is gasified in an atmosphere of the inert gas and mixed with the latter, a rotary diffusion-filter receiving the mixed gases and operative to progressively-separate the refrigerant gas from the inert gas, means for liquefying the refrigerant gas, means for separately conducting the liquefied refrigerant and filtered inert gas from the separator to the evaporator without further substantial admixture, and means controlling circulation of a small quantity of other liquid requisite in operation.

16. In refrigerating apparatus employing a refrigerant gas condensable at ordinary temperatures and an inert gas under pressure, evaporator means wherein the condensed refrigerant is gasified in an atmosphere of the inert gas and mixed with the latter, a multi-stage rotary diffusion-filter receiving the mixed gases and operative to progressively separate the refrigerant gas from the inert gas, means for liquefying the refrigerant gas, means for separately conducting the liquefied refrigerant and filtered inert gas from the separator to the evaporator without further substantial admixture, means accommodating circulation of a small quantity of lubricant requisite in operation, and means for extracting heat from the returning liquid and gas by absorption into the colder mixed gases.

17. In refrigerating apparatus employing a refrigerant gas condensable at ordinary temperatures and an inert gas under pressure, an evaporator wherein the condensed refrigerant is gasified in an atmosphere of the inert gas and mixed with the latter, a rotary diffusion-filter receiving the mixed gases and operative to progressively separate the refrigerant gas from the inert gas, a condenser for the refrigerant gas, means for separately returning the refrigerant and filtered inert gas to the evaporator, and means balancing the flow of the separated refrigerant and inert gases to control the degree of separation of the two gases.

18. In refrigerating apparatus employing a refrigerant gas condensable at ordinary temperatures and an inert gas under pressure, an evaporator wherein the condensed refrigerant is gasified in an atmosphere of the inert gas and mixed with the latter, a rotary diffusion-filter receiving the mixed gases and operative to progressively separate the refrigerant gas from the inert gas, a condenser for the refrigerant gas, means for separately returning the refrigerant and filtered inert gas to the evaporator, a hermetically sealed casing housing the diffusion filter and suitable rotating means, and means automatically balancing the flow of the refrigerant and inert gases returning to the evaporator.

19. In refrigerating apparatus employing a refrigerant gas condensable at ordinary

temperatures and an inert gas under pressure, an evaporator wherein the condensed refrigerant is gasified in an atmosphere of the inert gas and mixed with the latter, said evaporator being of U-shaped formation to accommodate ice trays, a rotary diffusion-filter receiving the mixed gases and operative to progressively separate the refrigerant gas from the inert gas, a condenser for the refrigerant gas, means for separately returning the refrigerant and filtered inert gas to the evaporator, a hermetically sealed casing housing the diffusion filter and suitable rotating means, and means automatically balancing the flow of the refrigerant and inert gases returning to the evaporator.

20. In a refrigerating apparatus employing a refrigerant gas condensable at ordinary temperatures and an inert gas under pressure, an evaporator wherein the condensed refrigerant is gasified in an atmosphere of the inert gas and mixed with the latter, a rotary diffusion-filter receiving the mixed gases and operative to progressively separate the refrigerant gas from the inert gas, a hermetically sealed casing housing said filter with suitable rotating means and having a gas tight connection to the evaporator, an integrally connected condenser for the refrigerant gas, means for returning the liquefied refrigerant to the evaporator including a trap accommodating escape of any uncondensed refrigerant gas, and separate means for returning the filtered inert gas to the evaporator.

21. In a refrigerating apparatus employing a refrigerant gas condensable at ordinary temperatures and an inert gas under pressure, an evaporator wherein the condensed refrigerant is gasified in an atmosphere of the inert gas and mixed with the latter, a rotary diffusion-filter receiving the mixed gases and operative to progressively separate the refrigerant gas from the inert gas, a hermetically sealed casing housing said filter with suitable rotating means and having a gas tight connection to the evaporator, an integrally connected condenser for the refrigerant gas, means for returning the liquefied refrigerant to the evaporator including a trap with an outlet for normal escape of any uncondensed refrigerant gas and a plurality of other controllable outlets accommodating additional escape under increased pressure of such gas as the admixture of inert gas increases, and separate means for returning the filtered inert gas to the evaporator.

22. In a refrigerating apparatus employing a refrigerant gas condensable at ordinary temperatures and an inert gas under pressure, an evaporator wherein the condensed refrigerant is gasified in an atmosphere of the inert gas and mixed with the latter, a rotary multi-stage diffusion-filter receiving

the mixed gases and operative to separate the refrigerant gas from the inert gas, a hermetically sealed casing housing said filter with suitable rotating means and having a sealed connection to the evaporator, an integrally connected condenser for the refrigerant gas, means for returning the liquefied refrigerant to the evaporator including a trap with a controlled outlet for normal escape of any uncondensed refrigerant gas and a plurality of other controllable outlets accommodating additional escape under increased pressure of such gas as the admixture of inert gas increases, and conduit means including an interposed regulatable valve for returning the filtered inert gas to the evaporator, both the trap and valve being housed in the sealed connection aforesaid.

23. In a refrigerating apparatus employing a refrigerant gas condensable at ordinary temperatures and an inert gas under pressure, an evaporator wherein the condensed refrigerant is gasified in an atmosphere of the inert gas and mixed with the latter, a sealed connection between the evaporator and a rotary multistage diffusion-filter receiving the mixed gases from evaporator, bearing means in said connection for the filter, a hermetically sealed casing housing said filter and suitable rotating means, a collection chamber for the separated refrigerant gas in said casing having conduit connection with the peripheral portion of the filter, a condenser for the refrigerant gas, and means for separately returning the liquefied refrigerant and filtered inert gas to the evaporator.

24. In a refrigerating apparatus employing a refrigerant gas condensable at ordinary temperatures and an inert gas under pressure, an evaporator wherein the condensed refrigerant is gasified in an atmosphere of the inert gas and mixed with the latter, a connection between the evaporator and a rotary multiple-diffusion separator receiving the mixed gases from said evaporator, bearing means in such connection, said separator embodying a hollow hub with a concentric annular ring connected by perforate members with intervening filter elements and a suitable filler, a hermetically sealed casing housing the separator and rotating means therefor, a collection chamber for the separated refrigerant gas in said casing having conduit connection with the separator ring proportioned to balance flow of the separated refrigerant and inert gas, a condenser for the refrigerant gas, and means for separately returning the liquefied refrigerant and filtered inert gas to the evaporator.

25. In a refrigerating apparatus employing a refrigerant gas condensable at ordinary temperatures and an inert gas under pressure, an evaporator wherein the condensed refrigerant is gasified in an atmosphere of the inert gas and mixed with the latter, a connection

between the evaporator and a rotary multiple-diffusion separator receiving the mixed gases from said evaporator, bearing means in such connection, said separator embodying a spool-like hub with a concentric annular ring rigidly connected by complementarily dished and central perforate members with intervening filter elements and a suitable filler, an imperforate casing about the separator, a hermetically sealed housing enclosing the separator and rotating means therefor, a collection chamber in said housing independent of the imperforate casing for the separated refrigerant gas, said casing having conduit connection with the separator annular ring proportioned to balance the flow of the separated refrigerant and inert gas, a condenser for the refrigerant gas, and means for separately returning the liquefied refrigerant and filtered inert gas to the evaporator.

26. In a refrigerating apparatus employing a refrigerant gas condensable at ordinary temperatures and an inert gas under pressure, an evaporator wherein the condensed refrigerant is gasified in an atmosphere of the inert gas and mixed with the latter, a connection between the evaporator and a rotary multiple-diffusion separator receiving the mixed gases from said evaporator, bearing means in such connection, said separator embodying a spool-like hub with a concentric hollow ring connected by complementarily dished and central perforate members with intervening filter elements and a suitable filler, an imperforate casing about the separator, a hermetically sealed housing enclosing the separator and rotating means therefor, a collection chamber in said housing independent of the imperforate casing for the separated refrigerant gas, said casing having conduit connection with the separator hollow ring, a condenser for the refrigerant gas, means for separately returning the liquefied refrigerant and filtered inert gas to the evaporator, and valve means controlling refrigerant gas flow to the condenser and return of the separated inert gas to the evaporator whereby a proper balance of their respective flow is maintained.

27. A refrigerating apparatus as claimed in the immediately preceding claim wherein the means for returning the liquefied refrigerant from the condenser to the evaporator includes a retroverted pipe section forming a trap having a top aperture for uncondensed gases, and a series of controlled apertures accommodating relief of excess gas.

In testimony whereof, I have hereunto signed my name at Philadelphia, Pennsylvania, this 21st day of March, 1931.

ARTHUR R. EARNSHAW. 125
